UNITED STATES PATENT OFFICE.

HERBERT R. BLISS, OF NIAGARA FALLS, NEW YORK.

SHIPPING CASE.

Application filed April 16, 1923. Serial No. 632,558.

To all whom it may concern:

Be it known that I, HERBERT R. BLISS, a citizen of the United States, residing at Niagara Falls, in the county of Niagara and 5 State of New York, have invented certain new and useful Improvements in Shipping Cases, of which the following is a specification.

This invention relates to a method for 10 sealing fiber shipping cases and has for its object an improved fiber shipping case which is so designed and calculated as to avoid some of the objections now urged against fiber shipping cases which are sealed 15 at the center. There are now on the market, fiber shipping cases which are sealed either by gluing the flaps together at the center with a silicate glue or by a sealing tape. The joint here is ordinarily a butt joint. There 20 are also on the market shipping cases sealed at the center by an overlap wire-stitched joint. These have been described and claimed in my prior applications, No. 514,788 and No. 501,620. I have also de- 25 scribed and claimed in a co-pending application No. 632,556 a method of coupling up abutting flaps at the center by wire-stitching, which as far as I know, has never here- 30 tofore been done.

However, some shippers, especially shippers of very heavy articles, object to the center sealing for the reason that the cases are sometime picked up by employees at the 35 ends of the cover wings and they sometimes tear here under such handling. It is the object of the present invention to eliminate this objection and make a shipping case which has a maximum strength at the sealing end.

40 In the drawings:

Fig. 1 is a perspective of the case after sealing.

Fig. 2 is a perspective of the unsealed case.

45 Fig. 3 is a plan view illustrating one step in the sealing operation.

Fig. 4 is a similar plan view illustrating another step in the sealing operation.

Fig. 5 is a section on the line 5—5 of 50 Fig. 3.

Fig. 6 is a section on the line 6—6 of Fig. 4.

Fig. 7 is a section on the line 7—7 of Fig. 4.

55 Figs. 8 and 9 are plan views illustrating a modified way of sealing.

Fig. 10 is a section on the line 10—10 of Fig. 9.

Fig. 11 is a plan view of the body blank 60 on a reduced scale.

Fig. 12 is a plan view of the end blank on a reduced scale.

Referring to Fig. 11, the body blank will be seen. It comprises a bottom, *a*, two sides *b*, *b*, and a top, *c*. This top is substantially 65 of the same width as the bottom. In the ordinary shipping case body blank, the cover wing is usually only half the width of the bottom or a little more than half to permit the slight overlap. Here, however, the top 70 wing is substantially the width of the case. On the opposite end of the blank I provide a narrow cover flap *d*.

The end blank is shown in Fig. 12, and 75 comprises a main end wall *e*, with three fastening flaps *f* at the bottom and two sides; the top has a sealing flap *g*.

It will be seen from inspection of Figs. 1 and 2 how the end and body blanks go together. The fastening flaps *f* fitting 80 around the sides and bottom and being secured thereto by a line of wire stitches *h*. However, no claim is made in the present application to this form of body building as the same has been described and claimed 85 in my prior applications No. 514,788 and No. 541,673. Furthermore, the specific form of the body construction has nothing to do with my invention which resides entirely in the top construction.

90 Now, by comparing Figs. 2 and 3, it will be seen how the top construction is made effective. The two sealing flaps *g* are turned in as is also the narrow cover flap *d*. The wide cover wing *c* is then folded down and a blade anvil *x* is inserted over the cover flap and under the sealing flaps and the cover wing. The stitches 1, 2, 3, 4, 5 are then taken. The anvil is then shifted to the opposite side of the case and stitches 6 to 95 10 inclusive, taken. The anvil may then be inserted at either of the two corners of the case at the end of the cover flap *d*. The stitch 11, (Figs. 4 and 6) may then be taken through three thicknesses at this point, and 100 the stitches from 12 to 18 inclusive, taken. The stitch 18, however, will not go through the sealing flap, but only through two thicknesses as shown in Fig. 7.

105 In Figs. 8 and 9, I have shown a slight modification in the way of sealing. With a relatively long case and short anvil, it is

desirable to begin the sealing of the cover wing and cover flap at the center as shown in Fig. 8, then reverse the case and work in again from the center as shown by stitches 5 15 to 18 in Fig. 9. However, each end of this line of stitches will go through only two thicknesses as shown in Fig. 10.

It will be obvious that any of the flaps or all could be on the outside of the cover 10 wing and sealed in this way, and I desire it understood that the claims are to be read to cover both ways.

What I claim is:

1. The method of sealing a three-blank 15 flush-end shipping case in which the end blanks are provided with sealing flaps and the side walls are provided one with a cover wing covering substantially the entire width of the case and the other side wall 20 with a relatively narrow cover flap, which method comprises the insertion of a blade anvil under the large cover wing and one of the sealing flaps, and the driving of metallic fasteners to fasten the cover wing along one 25 end to such sealing flap, then placing such anvil under the sealing flap at the opposite end and driving metallic fasteners through the large cover wing to fasten the cover wing at the other end, then the insertion of such anvil under the relatively narrow cover 30 flap and driving metallic fasteners along the remaining edge of the cover wing to complete the sealing of the box.

2. The method of sealing a three-blank 35 flush-end shipping case in which the end blanks are provided with sealing flaps and the side walls are provided one with a cover

wing covering substantially the entire width of the case and the other side wall with a relatively narrow cover flap, which method 40 comprises turning in the sealing flaps and the narrow cover flap, and then folding down the large cover wing over such sealing flaps and cover flap, the insertion of a blade anvil in at the side of the case over the 45 cover flap and stitching first one end of the cover wing to the underlying sealing flap, then the other end of the cover wing to the underlying flap, then the insertion of the blade anvil under the narrow cover flap and 50 the stitching of the third edge of the cover wing to such cover flap to complete the sealing of the case.

3. The method of sealing a three-blank 55 flush-end shipping case in which the end blanks are provided with sealing flaps and the body blank is provided with a cover wing and cover flap, which method comprises the insertion of a blade anvil under the large cover wing and one of the sealing 60 flaps, the driving of fasteners to fasten the cover wing along one end to such sealing flap, then placing such anvil under the sealing flap at the opposite end and driving fasteners through the large cover wing to fasten the cover wing at the other end, then the insertion of the blade anvil and clinching metallic fasteners thereon driven 65 through the cover flap to secure the third edge of the cover wing and complete the 70 sealing of the case.

In testimony whereof I affix my signature.

HERBERT R. BLISS.
